[57] CLAIM

The ornamental design for a tire, as shown and described.

DESCRIPTION

FIG. 1 is a perspective view of one side of a tire embodying my design, it being understood that the tread pattern is repeated uniformly throughout the circumference of the tire;

FIG. 2 is a front elevational view thereof;

FIG. 3 is a side elevational view of the one side thereof; FIG. 4 is a perspective view of the other side thereof; and,

FIG. 5 is a side elevational view of the other side thereof.

FIG. 1

FIG.2

FIG.3

FIG.4

FIG.5
